ELECTRIC WATER LIGHT

Charles Linhardt, Jr., Baltimore, Md.

Application February 20, 1943, Serial No. 476,580

5 Claims. (Cl. 9—8.3)

This invention is directed to a portable electric light, which while capable of a great variety of uses, is more particularly designed as a light which will float in the water, automatically light up when so floating, and provide illumination radiating in all directions from the light over the surface of the water.

The primary object of the present invention is the provision of a water light utilizing conventional and easily renewable batteries, and constructed to provide simplicity of assemblage and repair while practically immune to disabling injury under even extraordinary usage.

The improved electric water light provides for automatic energization and de-energization of the light bulb, and is so constructed that it will remain lighted in practically any position above the horizontal; the construction avoids the use of any mechanical equipment that can get out of order; and such construction by simple variation in part size can be made to accommodate the strength of the light bulb and any number of batteries, and its unitary construction is designed to provide easy and convenient renewal of light bulb and batteries, which are the only parts subject to renewal.

The invention is illustrated in the accompanying drawing, in which:

Figure 1 is a view in vertical section, partly in elevation, of the improved water light.

Figure 2 is a similar view showing the water light inverted.

Figure 3 is a detail perspective view of the connection between the lamp and the batteries.

The improved light includes a casing 1, preferably but not necessarily circular in section, and of greater length than diameter. The casing is diametrically reduced at the open upper end to provide a neck extension 2, exteriorly threaded at 3. The upper end of neck 2 has a narrow inturned flange or rounded portion 4, on which rests a conventional or selected reflector 5.

A transparent dome 6, preferably of plastic material, has an outstanding bottom edge flange 7, designed when the parts are assembled to overlie the reflector. An annular collar-like top 8 has an upper flange 9 to overlie and bear on the flange 7 of the dome and a depending interiorly threaded wall 10 to cooperate with the threaded portion 3 of the neck 2. The lower edge of the dome 6 may be flared as at 11 to fit beneath the flange of the top 8, a washer being interposed and the junction appropriately sealed. Thus, by operation of the collar top 8, the dome 6, preferably a unit with the top 8,

and the reflector 5 may be secured in sealed relation to the casing and the open upper end of the latter closed and sealed. If preferred, a spring sealing disc 12 may be interposed between the reflector and the rounded edge 4 of the neck 3.

A lamp socket 13 is secured to and depends below the reflector 5 to receive a light bulb 14 in position above the reflector, the socket forming one electrical connection to the light filament of the bulb. The socket 13 and bulb 14 are preferably formed for conventional bayonet-slot connection. The other, preferably the center electrical connection for the light bulb, is in the form of a rod-like element 15, passing through and insulated from the bottom of the socket 13. An angle plate 16 is secured to the rod 15 and insulated from the socket 13. The depending length 17 of the plate 16 is offset vertically from the rod 15 and carries an adjustable connector 18 for a wire connector to be later referred to.

A battery guide 19, in the form of a cylindrical body of less diameter and length than that of the casing 1, is arranged within and in axial coincidence with the casing, the guide being secured to the bottom of the casing 1. A weight 20 is secured to the closed bottom of the casing 1 and encircles and positions the lower end of the battery guide 19. The weight is of course sufficient to maintain the assembled light upright in the water with the dome and light bulb well above the normal surface of the water. The weight obviously acts when the assembled light is thrown or dropped in the water to cause the assembled unit to assume and maintain an upright light exposing position. The weight is secured to the bottom of the casing 1 and to the guide and may have a brass surface plate for better electrical connection.

40 A bottom inverted U-shaped stop 21 is secured in the lower end of the guide and is designed to support batteries 22 and form with the casing 1 one side of the battery circuit. Batteries 22 are arranged to reverse their normal arrangement, as shown, to avoid leakage in use, and the center contact 23 of the lowermost battery is in direct contact with the stop 21, a contact plate 24 being, if desired, arranged on the stop.

45 The batteries 22 in sufficient number to energize the light bulb 13 are of less aggregate length than that of the guide 19, and in the space above the upper battery and the contact element 18, there is provided a battery follower 25. The follower 25 is of non-conductive material, freely slidable in the guide 19 and provided at

each of its upper and lower ends with a metallic plate 26, these plates 26 being electrically connected by a metallic stem 27, such as a wire, passing through the follower. The lower end of the follower 25 and the lower plate 26 is separated by a fixed weight 27' secured to the follower to insure free and immediate gravitational movement of the follower in either position of the casing. The lowermost plate 26, in the operative position of the assembly, will contact with the normally bottom contact of the uppermost battery 22. The plates 26 are of less diameter than that of the follower proper to avoid contacting the guide 19. The upper plate 26 is connected by a flexible electrical conductor 28 to the element 18. The wire 28 is connected out of axial alignment with the follower by a metallic strip 29, secured electrically to the wire 27, and extends laterally of the center of the follower, with its terminal removably connected to the connector 18. The bulb 14 is in electrical connection with the batteries through the socket 13, the reflector 5, casing 1 and stop 21, the other side of the circuit being through follow contact plate 26, wire 27, wire 28, connection 18 and center contact rod 15.

The light assembly is normally stored or carried in an inverted position, that is, with the dome 6 down. The follower 25 thus moves toward the bulb 14 and the batteries follow, breaking the bottom contact at stop 21. When the assembly is to be used, for example, thrown into the water, the weight quickly arranges the unit with bulb 14 uppermost, while the inherent buoyance, incident to the sealed casing and trapped air, supports the unit with the dome 6 well above the normal surface of the water. As the casing assumes an operative position, the follower 25, incident to its superior weight, moves downwardly, forcing the batteries, which of course slide down by their own weight, into intimate and maintained contact with each other and with the stop 21. The superior weight of the follower is sufficient to maintain this contact under any usually rough condition of the water, thus preventing temporary disconnection of the batteries, due to wave action which would cause an intermittent light instead of the desired constant and steady light resulting from the use of the follower.

Obviously, renewal of batteries or other parts is easily permissible by simply removing the collar top 9. The various parts of the assembly may be constructed of any appropriate material, and no limitation is contemplated in this respect.

What is claimed is.

1. A portable light for free floating in the water, including a casing, a dome overlying the casing, a reflector at the upper end of the casing, removable means for securing the dome, reflector and casing together to seal the interior of the casing, a light socket secured to and depending below the reflector and adapted to receive a light bulb, a battery guide extending longitudinally in and spaced from the casing, a battery contact at the lower end of the guide and having electrical connection with the casing, said guide serving to slidably receive one or more conventional batteries, a weighted battery follower slidably fitting in said guide, and means carried by said follower to electrically connect one side of the battery circuit to an appropriate contact of the light socket, the other side of the battery circuit being connected to the remaining contact of the lamp socket through the casing and reflector.

2. A construction as defined in claim 1, wherein the upper end of the casing has a reduced-diameter extension to receive the dome and reflector and cooperate with the securing means for such parts, said extension being concentric with and of relatively increased diameter with respect to the guide, whereby on removal of such securing means the dome, reflector, battery follower and batteries may be freely removed from or replaced in operative position without operation of any securing or fastening means.

3. A construction as defined in claim 1, wherein the battery follower includes an insulating body accurately fitting for free sliding in the guide, said follower having a weight at one end.

4. A construction as defined in claim 1, wherein the battery follower includes an insulated body accurately fitting for free sliding in the guide, said follower having a weight at one end, said weight being of conductive material, a flexible conductor removably fixed to the upper end of the follower, and a conductor extending through the follower and electrically connecting the weight and the flexible conductor.

5. A construction as defined in claim 1, wherein the casing is formed at the upper end to provide a diametrically-reduced externally-threaded extension, the upper end of the extension being formed to support the reflector and dome, and wherein the securing means includes a threaded element to cooperate with the threaded extension and hold the reflector and dome in position.
